CLAIM

The ornamental design for interlocking bracket, as shown and described.

DESCRIPTION

FIG. 1 is a perspective view of the joined parts of the interlocking bracket of my design;

FIG. 2 is a top plan view thereof;

FIG. 3 is a bottom plan view thereof;

FIG. 4 is a front elevational view thereof;

FIG. 5 is a right side elevational view thereof, which is a mirror image of the left side elevational view;

FIG. 6 is a rear elevational view thereof; and,

FIG. 7 is a perspective view of the parts thereof separated. The elements of the claimed design are shown broken away for clarity of illustration.
